INVENTOR-

F. P. Murphy

UNITED STATES PATENT OFFICE.

FRANCIS P. MURPHY, OF NASHUA, NEW HAMPSHIRE, ASSIGNOR TO UNITED SHOE MACHINERY CORPORATION, OF PATERSON, NEW JERSEY, A CORPORATION OF NEW JERSEY.

SHOE RACK.

Application filed July 19, 1926. Serial No. 123,587.

This invention relates to shoe racks such as are used to carry shoes from one part of a factory to another and to hold the shoes between operations performed upon them.

It was formerly customary to employ several different types of shoe racks especially adapted for use in connection with the various operations performed in shoe-making. More recently, from considerations of economy of floor space and maintenance of racks, some factories have adopted a single type of rack construction for use in connection with most or all of the operations performed upon shoes.

One rack construction which has come into general use for this reason is that of the type disclosed in United States Letters Patent No. 1,556,425, granted October 6, 1925, upon an application filed in the name of W. E. Coombes et al., which comprises relatively flat shoe-supporting members, or pins, arranged for contacting with the heel parts of uppers of shoes carried in the rack bottom side up, a toe rest being provided to assist in positioning and supporting the foreparts of the shoes. Racks of the type referred to are used normally for carrying lasts or shoes, bottom side up, between operations performed upon shoes from the time the lasts are picked until the lasts are removed from the shoes.

To adapt such racks to use in connection with the finishing operations performed upon shoes, in which case it is desirable to carry shoes right side up, a cover, preferably made of flannel, is placed upon the pins. This cover prevents the heels of shoes from dropping down into the spaces between the pins, and serves to prevent discoloration of the shoes by contact with the shoe-supporting members.

It is customary to construct the pins of racks of the type above described in accordance with the needs of the various factories making use of such racks. This is done by shaping and spacing the pins to correspond approximately to the average size of shoe of a range of sizes of shoes to be carried in a rack. In this way a single rack can be made to carry any size of one specific kind of shoes, such as men's, women's, or boys' shoes, which a particular factory is likely to make. However, because of the great difference in shapes and sizes existing between men's and women's

shoes, and between men's and boys' shoes, it has been found to be impractical to employ a rack, originally designed for carrying one kind of shoes, for use in connection with another kind of shoes. For example, it is practically impossible to carry boys' shoes on a rack designed for carrying men's shoes, for the reason that the spacing between the pins in the rack is such that shoes of the relatively small sizes will drop through the pins. Accordingly, it has heretofore been customary to employ racks having differently spaced pins for use in making the various kinds of shoes mentioned. Thus, it has been necessary, in factories making more than one kind of shoes, to maintain at hand more than one set of racks with the consequent additional expense of maintenance and loss of valuable floor space during such times as one or more sets of racks are not in use.

In view of the foregoing, the present invention provides an improved rack convertible for different uses in carrying shoes, in which shoe supporting and positioning members are arranged for adjustment relatively to each other to adapt the rack for use in carrying shoes of widely different sizes.

Preferably, and as herein illustrated, the rack is provided with a bar movable along shoe-supporting pins into position in any one of a plurality of sets of grooves in the body portion of the rack so that the bar may be located to position and support the foreparts of shoes of either large or small sizes, bottom side up, or to act as a heel stop for shoes carried in the rack in upright position.

These and other features of the invention comprising certain combinations and arrangements of parts will be understood from the following description of a preferred embodiment of the invention and as illustrated in the accompanying drawings, in which

Fig. 1 is a perspective view of the rack embodying the present invention;

Figs. 2, 3 and 4 are views showing a part of the rack, with the adjustable bar located in its several operative positions; and

Fig. 5 is a detail view of one end of the bar.

The illustrated rack, as shown in Fig. 1, comprises bottom frame members 10 and end frame members 12 composed of steel angle sections secured together to form a rigid structure by means of braces 14 and 16, diagonals 18 and 20, and a tie rod 22. The

bottom frame members 10 are provided with casters 24 and bumpers 26 of well-known construction. Spaced from the bottom members 10 are bars 28 and cross pieces 30 which form a shelf for carrying boxes containing shoe parts.

Riveted to inner portions of the end members 12 are channel sections 32 positioned to engage and support wooden shelves 34 which 10 constitute the shoe-supporting portions of the rack.

Each of the shelves 34 (see Figs. 1 and 2) comprises end pieces 36 connected by a back rail 38 and a pin bar 40. Secured to the upper 15 surface of the pin bar 40 by means of screws 42 are a plurality of shoe-supporting members or pins 44, the rear ends of which are received in a groove 46 formed in the back rail 38. The pins adjacent the end pieces 36 are 20 positioned in grooves 48. The bar 40, groove 46, and grooves 48 are inclined to the horizontal in such manner that the pins 44 are supported with their free ends tilted upwardly toward the front of the rack. The 25 construction just described provides means for securely supporting the pins, but at the same time readily permits removal of the pins for purposes of replacement.

The pins are of the alternate wide and 30 narrow construction disclosed in the aforementioned patent, and are adapted normally to receive and support between them shoes in inverted position with the heel portions of the uppers of the shoes in contact with 35 the edges of the pins.

Means is provided for assisting in the supporting and positioning of shoes of large sizes as well as small sizes either in inverted position or in upright position. As herein 40 shown, this means comprises a bar 50 provided at each end with a tenon 52 as illustrated in Fig. 4. The end pieces 36 of each shelf are provided with three sets of substantially vertical grooves 54, 56 and 58, equally 45 spaced from the back rail 38 at opposite ends of the shelf and shaped to receive the tenoned ends of the bar 50. The tenons 52 and the walls of the grooves 54, 56 and 58 form inter-engaging parts operable to hold the bar 50, 50 selectively, in any one of three positions in each of which the bar extends across the pins parallel to the back rail. The three operative positions of the bar are illustrated in Fig. 1 in connection with the showing of the top, 55 second and third shelves respectively.

The use of the rack is best illustrated with reference to Figs. 2, 3 and 4.

As indicated in Fig. 2, the bar 50 is positioned in the grooves 54 which are so spaced 60 relatively to the shoe-supporting edges of the pins 44 as to locate the bar in position to act as a toe rest for large shoes, such as shoe 60, the heel portion of which is supported upon the edges of the pins 44. This constitutes the normal use of the rack, the bar 50

ordinarily being left in the position shown until the rack is to be used as a treeing and packing room rack. The bar 50 is then removed from the grooves 54, a cover 62 of flannel, paper or other sheet material 70 is placed over the pins, as shown in Fig. 3, and the bar is inserted in the grooves 58. In this position the bar acts as a heel stop for shoes such as shoe 64 placed on the cover 62, in upright position with its 75 shank extending over the bar 50 and its heel in contact with that portion of the bar facing toward the front of the rack. The inclination of the pins assists in maintaining the heels of shoes in contact with the bar. In 80 this manner shoes are carried with their bottom portions firmly supported, with their uppers out of contact with the back rail of the rack, and at the same time, the shoes are so positioned with their heel ends extending outwardly as to be readily accessible from the 85 front of the rack.

When it is desired to carry shoes of smaller size than can be supported upon the rack with the bar positioned as shown in Fig. 2, the bar 90 50 is moved into the intermediate grooves 56. As illustrated in Figs. 1 and 4, the grooves 56 are so spaced relatively to the shoe-supporting edges of the pins 44 as to locate the bar 50 in position to act as a toe rest for the 95 foreparts of small shoes such as shoe 66 carried in inverted position, the heel portions of the shoes being supported on the edges of the pins 44 in substantially the same manner as shoes of larger sizes. For carrying small 100 shoes in upright position, the bar 50 is placed in grooves 58 and the shoes are carried in the same manner as described in connection with carrying large shoes in upright position.

It will thus be apparent that I have provided a convertible shoe rack which is selectively adapted for use throughout the entire process of shoe-making for carrying shoes over a wide range of sizes, either in inverted 105 position or upright position.

Having described my invention, what I claim as new and desire to secure by Letters Patent of the United States is:—

1. A shoe rack comprising a frame, end pieces supported in the frame, a pin bar connecting the end pieces, shoe-supporting pins mounted on the pin bar, a movable toe rest extending across the pins, grooves in the end pieces for locating the toe rest in position to support the foreparts of shoes of large sizes, 115 and additional grooves in the end pieces for locating the toe rest in position to support the foreparts of shoes of small sizes.

2. A shoe rack shelf comprising end pieces, a plurality of shoe-supporting members, and a shoe-positioning member normally extending across the shoe-supporting members, the end pieces being provided with a plurality of grooves for co-operating with the positioning member selectively to locate it in position 125 130

to act as a toe rest for relatively large shoes, in position to act as a toe rest for relatively small shoes, or in position to act as a heel stop for shoes carried in the rack in upright 5 position.

3. A shoe rack for carrying shoes of widely different sizes comprising a plurality of members constructed and arranged to support shoes in inverted position, a shoe-positioning member 10 extending across the shoe-supporting members, and means for co-operating with the shoe-positioning member selectively to locate it relatively to the shoe-supporting members in position to engage with and to support shoes of the larger sizes or in position 15 to engage with and to support shoes of the smaller sizes.

4. A shoe rack for carrying shoes of widely different sizes comprising pins for supporting heel portions of shoes carried in the rack in inverted position, a positioning member 20 extending across the pins for supporting the foreparts of the shoes, and means for selectively locating the positioning member along the pins in position to support the foreparts 25 of shoes of the larger sizes or in position to support the foreparts of shoes of the smaller sizes.

5. A shoe rack for carrying shoes of widely 30 different sizes comprising shoe-supporting members, and a shoe-positioning member extending across the supporting members, the supporting members and the positioning

member having interengaging portions for locating the positioning member relatively to 35 the shoe-supporting members in position to act as a toe rest for shoes of the larger sizes or in position to act as a toe rest for shoes of the smaller sizes.

6. A shoe rack comprising a plurality of 40 shoe-supporting pins having their outer ends shaped to receive between them and to support the heel portions of shoes carried in the rack, a positioning member extending across the pins, means for locating the positioning 45 member relatively to the pins in position to support the foreparts of shoes of the larger sizes, and means for locating the positioning member relatively to the pins in position to support the foreparts of shoes of the smaller 50 sizes.

7. A shoe rack for carrying shoes of widely different sizes comprising a plurality of pins having edges for engaging with and for supporting the heel portions of the shoes, a bar 55 extending across the pins for maintaining the shoes in position upon the pins, and means for selectively locating the bar along the pins in spaced relation to the shoe-engaging edges thereof in position to support the foreparts 60 of shoes of the larger sizes or in position to support the foreparts of shoes of the smaller sizes.

In testimony whereof I have signed my name to this specification.

FRANCIS P. MURPHY.
